UNITED STATES PATENT OFFICE.

JOHN H. RANDALL, OF SALINA, KANSAS.

ADJUSTABLE WHEEL CLAMP.

Application filed June 12, 1925. Serial No. 36,714.

To all whom it may concern:

Be it known that I, JOHN H. RANDALL, a citizen of the United States, residing at Salina, in the county of Saline and State of Kansas, have invented certain new and useful Improvements in Adjustable Wheel Clamps, of which the following is a specification.

This invention relates to wheel anchors especially adapted for use while removing or renewing journal box bearings on railway rolling stock.

Briefly stated, an important object of this invention is to provide a wheel anchor or clamp having simple means whereby a wheel may be held in place during the removal and possible renewal of a journal box bearing without necessitating the employment of separate levers, or the like, and without the aid of more than one man.

A further object is to provide a wheel clamp or anchor which may be quickly adjusted for use in connection with rails of different sizes and which may be mounted on the road bed or the ties, depending on the position of the wheel.

A further object is to provide a wheel anchor of the character specified which is of highly simplified construction, durable in use, and cheap to manufacture.

Other objects and advantages will be apparent during the course of the following description.

In the accompanying drawing forming a part of this application and in which like numerals are employed to designate like parts throughout the same,

Figure 1 is a side elevation of the improved clamp in use;

Fig. 2 is a vertical sectional view taken on line 2—2 of Fig. 1;

Fig. 3 is a horizontal sectional view taken on line 3—3 of Fig. 2;

Fig. 4 is a vertical sectional view through the clamp employed in connection with a larger size rail than that illustrated in Fig. 2.

In the drawing, wherein for the purpose of illustration is shown a preferred embodiment of the invention, the numeral 5 designates an elongated base or block which as illustrated in Fig. 1 is of sufficient length to span the space between and rest upon the ties 6 of a track, one rail of the latter being designated by the numeral 7. The block 5 may be of any suitable material

and is stout enough to support the weight of a car. Figs. 1 and 2 plainly illustrate that a screw or other jack 8 is detachably mounted on the base 5 and adjustably supports the bearing box 9 so that the bearing may be renewed in the usual manner. It is important to note that the jack 8 may be of standard construction and is not in any way modified by or permanently connected to any of the parts of the improved wheel clamp or anchor so that in case the anchor is broken another anchor may be employed, or in case the jack is broken another jack may be employed.

Figure 3 illustrates that a pair of substantially L-shaped brackets 11 are secured to one side of the block 5 by fastening bolts 12 or other suitable means and are provided with laterally projecting ears 14 having aligned pairs of openings 15 for selectively receiving a pivot bolt 16 by means of which a clamping arm 18 is adjustably attached to the brackets. Figs. 2 and 4 illustrate that the upper portion of the arm 18 is provided with a laterally projecting branch 20 which overhangs and engages the flange 21 of the wheel 22 to hold the wheel in place during the renewal of the journal bearing.

The laterally projecting branch 20 is held firmly in engagement with the flange 21 by a holding bar 26 having a curved head 28 which detachably engages one side of the jack 8. The other end of the bar is bifurcated to provide a pair of branches which fit on opposite sides of the arm 18 and which are provided with aligned openings 30 for selectively receiving a pivot bolt 32 by means of which the holding bar is adjustably and pivotally connected to the arm 18.

It will be seen that the arm 18 which carries the holding bar 26 may be conveniently engaged with the wheel to hold the same in place on the rail 7 during the renewal of the journal bearing or brass. As the arm 18 is adjustably connected to the ears 14, the parts may be quickly positioned for use in connection with a comparatively low rail as shown in Fig. 2 or a higher rail as shown in Fig. 4. The use of this invention dispenses with the necessity of employing a second man to hold the wheel in place during the renewal of the brass. Also, the need of employing a separate lever is overcome.

Attention is directed to the fact that the clamping mechanism is more or less independent of although used in conjunction

with the screw jack. This permits any style of jack to be employed. The base 5 may be employed without the possibility of the same sinking into the road bed, and in the use of this invention the same will effectively hold the wheel in place during the renewal of the brass.

Having thus described the invention, what is claimed is:

- 10 1. A wheel anchor comprising a base, a bracket connected to one side of the base, a clamping arm adjustably and pivotally connected to the bracket and having means for engaging a wheel to hold the same in place, said base being adapted for detachably supporting a jack, and a holding bar adjustably and pivotally connected to said arm and adapted to detachably bear against one side of the jack mounted on said base.

15 2. A wheel clamp comprising an elongated base adapted to rest upon one or more ties and adapted to support a jack, L-shaped brackets secured to one vertical side of said base and having laterally projecting apertured ears provided with spaced pairs of openings, a clamping arm positioned between said ears, a pivot bolt selectively extending through said openings and pivotally connecting said arm to said ears, the upper portion of said arm being provided with a laterally projecting branch to overhang and engage a flange of a wheel to hold the wheel in place and a holding bar adjustably and pivotally connected to said arm in order to bear against one side of the jack.

20 3. A wheel clamp comprising an elongated base adapted to rest upon one or more ties and adapted to support a jack, L-shaped brackets secured to one vertical side of said base and having laterally projecting apertured ears provided with spaced pairs of openings, a clamping arm positioned between said ears, a pivot bolt selectively extending through said openings and pivotally connecting said arm to said ears, the upper portion of said arm being provided with a laterally projecting branch to overhang and engage a flange of a wheel to hold the wheel in place and a holding bar adjustably and pivotally connected to said arm in order to bear against one side of the jack.

25 4. A wheel clamp comprising an elongated base adapted to rest upon one or more ties and adapted to support a jack, L-shaped brackets secured to one vertical side of said base and having laterally projecting apertured ears provided with spaced pairs of openings, a clamping arm positioned between said ears, a pivot bolt selectively extending through said openings and pivotally connecting said arm to said ears, the upper portion of said arm being provided with a laterally projecting branch to overhang and engage a flange of a wheel to hold the wheel in place and a holding bar adjustably and pivotally connected to said arm in order to bear against one side of the jack.

30 5. A wheel clamp comprising an elongated base adapted to rest upon one or more ties and adapted to support a jack, L-shaped brackets secured to one vertical side of said base and having laterally projecting apertured ears provided with spaced pairs of openings, a clamping arm positioned between said ears, a pivot bolt selectively extending through said openings and pivotally connecting said arm to said ears, the upper portion of said arm being provided with a laterally projecting branch to overhang and engage a flange of a wheel to hold the wheel in place and a holding bar adjustably and pivotally connected to said arm in order to bear against one side of the jack.

35 6. A wheel clamp comprising an elongated base adapted to rest upon one or more ties and adapted to support a jack, L-shaped brackets secured to one vertical side of said base and having laterally projecting apertured ears provided with spaced pairs of openings, a clamping arm positioned between said ears, a pivot bolt selectively extending through said openings and pivotally connecting said arm to said ears, the upper portion of said arm being provided with a laterally projecting branch to overhang and engage a flange of a wheel to hold the wheel in place and a holding bar adjustably and pivotally connected to said arm in order to bear against one side of the jack.

40 7. A wheel clamp comprising an elongated base adapted to rest upon one or more ties and adapted to support a jack, L-shaped brackets secured to one vertical side of said base and having laterally projecting apertured ears provided with spaced pairs of openings, a clamping arm positioned between said ears, a pivot bolt selectively extending through said openings and pivotally connecting said arm to said ears, the upper portion of said arm being provided with a laterally projecting branch to overhang and engage a flange of a wheel to hold the wheel in place and a holding bar adjustably and pivotally connected to said arm in order to bear against one side of the jack.

connecting said arm to said ears, the upper portion of said arm being provided with a laterally projecting branch to overhang and engage a flange of a wheel to hold the wheel in place, and a holding bar pivotally and adjustably connected to the upper portion of said clamping arm adjacent said laterally projecting branch and having a curved head to rest against one side of the jack mounted on said base whereby to hold said clamping arm in engagement with said flange of the wheel. 45 50 55

4. A wheel clamp comprising an elongated base adapted to rest upon one or more ties and adapted to support a jack, L-shaped brackets secured to one vertical side of said base and having laterally projecting apertured ears provided with spaced pairs of openings, a clamping arm positioned between said ears, a pivot bolt selectively extending through said openings and pivotally connecting said arm to said ears, the upper portion of said arm being provided with a laterally projecting branch to overhang and engage a flange of a wheel to hold the wheel in place, and a holding bar pivotally and adjustably connected to the upper portion of said clamping arm adjacent said laterally projecting branch and having a curved head to rest against one side of the jack mounted on said base whereby to hold said clamping arm in engagement with said flange of the wheel, said holding bar being bifurcated to provide a fork, the sides of which have registering openings positioned at opposite sides of the laterally projecting branch of said clamping arm, and a pivot element selectively extending through said openings in said holding bar and through said arm to adjustably connect the holding bar to the arm.

In testimony whereof I affix my signature.
